UNITED STATES PATENT OFFICE.

WILLIAM C. AUSTIN, OF PHILADELPHIA, PENNSYLVANIA, ASSIGNOR TO DAVID P. AUSTIN, OF PHILADELPHIA, PENNSYLVANIA.

PATTERN WHEEL FOR KNITTING MACHINES.

Application filed May 22, 1926. Serial No. 111,005.

My invention relates to pattern wheels for circular knitting machine, the principal object of the invention being to construct such a wheel in a simplified manner compared 5 with the wheels of the same general character in use at the present time.

Another object of the invention is to construct the wheel in such a manner that it will not be necessary to remove the wheel from 10 the machine, to which it is adapted, when it is desired to make a change in the pattern of the fabric to be knit upon the knitting machine.

Other objects and details of the invention 15 will be more fully disclosed hereinafter, reference being had to the accompanying drawings, of which:

Fig. 1 is a plan view of my improved pattern wheel, illustrating the position it would 20 occupy, when attached to a knitting machine, relative to the needles of the knitting machine;

Fig. 2 is a sectional elevation taken along the line 2—2 of Fig. 1;

Fig. 3 is a sectional elevation taken along the line 3—3 of Fig. 1; and

Fig. 4 is a plan view of the major element included in my improved pattern wheel.

My improved pattern wheel is adapted to 30 be rotatably mounted on the cam ring of a circular knitting machine, regardless of whether the machine be of the revolving cylinder type or the stationary cylinder type, the wheel being adapted to engage the butts 35 of the knitting needles thereof and to be rotated by the relative movement between the cam ring and the knitting cylinder, its primary object being to engage the butts of certain of the needles for the purpose of raising 40 them from the normal knitting plane to a plane wherein they will not be affected by the stitch cam of the machine and will, therefore, retain the stitch, previously formed thereon, for the purpose of forming a design 45 in the fabric being knit. The needles are subsequently lowered to the normal knitting plane to perform regular knitting by means forming no part of the present invention.

As shown particularly in Fig. 3, my im- 50 proved pattern wheel comprises a body portion 1 in the form of a disc, and is provided with a hub 2 having a circular opening 3 for the reception of a stud adapted to be secured on the cam ring of the machine and upon 55 which the wheel revolves. The periphery of

the disc 1 is provided with a series of equally spaced and radially disposed grooves 4, between which are formed radially disposed tongues 5.

As illustrated in Fig. 2, the grooves 4 and 60 the tongues 5 are formed at an angle with respect to, and across the face of, the disc 1, and in a vertical plane parallel to the plane of movement of the needles with which the wheel co-operates. As illustrated in Fig. 2, 65 the disc 1 revolves in a plane disposed at an angle with respect to the plane of the needles and to the normal knitting plane thereof, one side of the wheel being disposed below the normal knitting plane and the opposite side 70 thereof being disposed above the normal knitting plane, as clearly illustrated in said figure.

The disc 1 is provided with an annular groove 6 whereby an annular shoulder 7 is 75 formed in the disc. Pins 8 are adapted to be placed on the disc 1, each having one end engaging the annular shoulder 7, the opposite end thereof extending into one of the grooves 4 and between the adjacent tongues 5, the 80 bottom side of the pin resting on the base of the annular groove 6 and the upper side thereof being adapted to be engaged by a retaining plate 9. Screws 10 are provided and pass through the retaining plate 9 and into threaded apertures formed in the disc 1, whereby 85 the pins 8 are securely clamped between the base of the annular groove 6 and the under side of the plate 9. The plate 9 is provided with a hub 11 which encircles the hub 2 of 90 the disc 1. The upper side of the pins 8 lie in a plane slightly below the upper edge 12 of the tongues 5, whereby a pocket is formed 95 for the purpose of receiving the butt 13 of a knitting needle 14.

In operation the pins 8 are placed in cer- 100 tain of the grooves 4, in accordance with the design desired to be knit in the fabric, the remaining grooves being open to receive but not to affect the operation of the remaining needles. As the needles revolve relative to the 105 rotational centre of the wheel, the butts of the successive needles enter the successive grooves 4 of the wheel and thereby rotate the wheel. Where no pin 8 is positioned in the 110 groove, the needle pursues the normal knitting plane illustrated at *x* in Fig. 2, but when a pin 8 is positioned in the groove 4, the needle registering with that particular groove is raised to the plane illustrated at *y*

in said figure for the purpose hereinabove stated.

In order to alter the pattern of the fabric being knit, it is not necessary to remove the wheel from its position on the cam ring, and by simply backing off the screws 10 and thereby releasing the pins from the frictional engagement of the plate 9 and the base of the groove 6 formed in the disc 1, the individual pins may be removed from and replaced in any desired position in the wheel, simply by the use of a pair of pointed pliers capable of entering any of the grooves 4. When the desired change is completed the screws 10 are again tightened, and the wheel is thereby placed in condition for operation.

It will be understood that while I have shown pins of cylindrical or circular form in cross-section, I am not limited to the use of this form, as the pins may be of a rectangular or any other desired form in cross-section.

Having disclosed one embodiment of my invention, various modifications will inevitably present themselves to one familiar with mechanical arts, therefore, only such limitations should be placed upon the scope of my invention as prescribed by the appended claims, or dictated by the prior art of record.

I claim:

1. In a pattern wheel, adapted to be used in conjunction with a knitting machine, comprising a circular disc having a concentric groove and a plurality of radially disposed

grooves formed therein, the said radial grooves extending between the outer wall of said concentric groove and the periphery of the wheel and the inner wall of said concentric groove forming an abutment in radial alignment with said radially disposed grooves; cylindrical pins having the same cross-sectional configuration throughout their entire lengths, located in said radial grooves with one end in contact with said abutment; and means for securing said pins in position.

2. In a pattern wheel, adapted to be used in conjunction with a knitting machine, comprising a circular disc having a concentric groove and a plurality of radially disposed grooves formed therein, the said radial grooves extending between the outer wall of said concentric groove and the periphery of the wheel and the inner wall of said concentric groove forming an abutment in radial alignment with said radially disposed grooves; pins located in said radial grooves with one end in contact with said abutment; a retaining plate overlying said circular disc; an annular depending flange on said retaining plate, adapted to fit within said concentric groove and engage said pins therein; and means for pressing the said flange against said pins and thereby press the pins against the base of said concentric groove, for rigidly maintaining said pins in position.

WILLIAM C. AUSTIN.
